UNITED STATES PATENT OFFICE.

MARSHMAN W. HAZEN, DECEASED, LATE OF NEW YORK, N. Y., BY JOSIAH O. HAZEN,
OF HAVERHILL, MASSACHUSETTS, ADMINISTRATOR; SAID MARSHMAN W. HAZEN
ASSIGNOR TO CORONA TYPEWRITER COMPANY, INCORPORATED, A CORPORATION
OF NEW YORK.

TYPE-WRITING MACHINE.

1,247,110.

Specification of Letters Patent.

Patented Nov. 20, 1917.

Original application filed June 23, 1908, Serial No. 439,967. Divided and this application filed August 28,
1913, Serial No. 786,707. Renewed April 19, 1917. Serial No. 163,311.

To all whom it may concern:

Be it known that I, JOSIAH O. HAZEN, a citizen of the United States, and a resident of Haverhill, county of Essex, State of Massachusetts, administrator of the estate of MARSHMAN W. HAZEN, late a citizen of the United States and resident of the city, county, and State of New York, deceased, make application for certain new and useful 10 Improvements in Type-Writing Machines invented by the said MARSHMAN W. HAZEN, of which the following is a full, clear, and exact description.

This invention relates more particularly 15 to the line lock mechanism of front strike or visible typewriting machines in which the carriage is adapted to be folded or shifted forward when not in use to make the machine more compact, and is a division of the 20 application of Marshman W. Hazen, Serial No. 439,967, filed June 23, 1908, now Patent No. 1,121,094, dated December 15, 1914.

The primary object of the invention is to provide simple and efficient means whereby 25 the platen carriage may be automatically locked against movement at the end of a line and after being released may move a short distance for the purpose of adding one 30 or more characters and the carriage again automatically locked against further movement.

Another object of the invention is to provide simple and efficient means whereby a 35 part of the key-operated mechanism may be positively locked and thereby prevent the depression of the key-operated levers.

A further object of the invention is to provide simple means movable with the carriage which is adapted to operate an element or member supported on a fixed part 40 of the machine and which when moved will directly engage and positively lock a part of the feed mechanism against movement.

With these and other objects in view, the 45 invention will be hereinafter more particularly described with reference to the accompanying drawings, which form a part of this specification, and will then be pointed out in the claims at the end of the description.

In the drawings, Figure 1 is a fragmentary longitudinal section of one form of

typewriting machine embodying the invention.

Fig. 2 is a fragmentary rear elevation of 55 the upper part of the machine.

Fig. 3 is a fragmentary inverted plan, partly in section, of one form of line lock mechanism.

Fig. 4 is a fragmentary sectional plan of 60 the member of the line lock mechanism which travels with the carriage, and

Fig. 5 is a transverse section taken on the line V—V of Fig. 4.

While the invention as shown is more 65 particularly adapted to the form of typewriting machine disclosed in the patent granted to Frank S. Rose, No. 948,553, dated Feb. 8, 1910, in which the carriage and platen has a vertical shift and is adapted to 70 fold over in overhanging relation to the keys, and in which the type-bars have a front strike for visible writing, it is to be understood that the invention is equally adapted for use in connection with other 75 forms of typewriting machines, and that the invention is not limited to the particular construction and arrangement of the parts herein shown.

The frame 10 may be of any suitable construction and may comprise the side plates 11 and the rear plate 12. Held to the side plates 11 transversely of the machine are one or more supports 13 on which are suspended a number of key-operated levers 14. These 85 levers are normally forced in one direction by springs 15 and at their rear or inner ends are each connected by a link 16 to a type-bar 17. Each type-bar 17 is pivoted at 18 to a bracket or support 19, and at its outer end 90 has a head or type block 20 on which are a plurality of characters 21 indicating the upper and lower case and figures in the usual way. The type blocks 20 are adapted to be moved against the platen 21 when the 95 levers 14 are depressed for letter writing. The platen is mounted to rotate in a carriage 22. This carriage 22 moves transversely of the machine along a bed 23. The bed 23 is held to the bars or members 24 of a foldable 100 support in substantially the same manner as disclosed in the patent referred to herein.

The universal bar 25 is located over the levers 14 and the spacing levers and is con-

ected at opposite ends by links 26 to bell-crank levers 27. There are two bell-crank levers, one located at each side of the machine, and said bell-crank levers are pivoted at 28 and have their arms 29 each provided with a screw 30, the body of each of which is adapted to pass through a slot 31 on one of the rocking arms 32. The arms 32 are two in number and are located at opposite sides of the machine and are pivotally held to rock on a transversely extending rod 33 located at the lower portion of the machine. These arms 32 are connected together by a transversely extending bar 38 and said bar 15 together with the arms 32 form a rocking frame which is actuated each time one of the levers 14 or the spacing levers are operated. This rocking motion is accomplished by the universal bar 25 being forced upwardly as 20 each lever 14 is depressed, which causes the bell-crank levers to be moved and through the arms 29 and screws 30 forces the rocking arms back and forth, there being a spring, not shown, or other means provided for restoring the parts to their normal position.

As a means for letter spacing, the carriage 22 is provided with a rack 34, the teeth of which are engaged by the dogs 35 and 36 of the dog carrier 37. The dog carrier 37 is pivoted at 38 to cause the dogs mounted thereon to move transversely of the teeth of the rack 34. The loose dog 35 may be held by one or more springs 39, and when the dog carrier is moved will permit 40 the carriage through its tension mechanism including the usual spring drum and cord 40 to be forced a single space for letter writing in the usual way. The parts thus described may be of the usual or of any preferred construction and may be operated in any desired manner.

It is desirable to lock the carriage at the end of a line, and it is also desirable to permit the carriage to move far enough to add 45 one or two letters to any of the lines in case a word is not finished properly. This may be effected in various ways. As shown, the arm 41, Fig. 2, to which the cord or flexible connection 40 from the spring drum is attached and which rings the bell, has a dog or locking device 42 pivotally held thereto and normally pressed inward by a spring 43. This device is held against rotary movement 50 by the parts 44 of a bracket 45 and extends 55 outward on opposite sides of its pivoting point, one part, as at 46, to serve as a handle, and the other part, as 47, being provided with a slot 48. An arm or lever 49 is pivoted, at 50, under the carriage bed 23 at 60 the rear thereof, and has one end adapted to be engaged by the end or abutment 51 of the device 42, and its inner end adapted to be forced into the path of movement of the dog carrier 37 or the outer dog to engage the 65 same and prevent action of the dogs 35 and

36. The lever 49 is normally forced in one direction by a spring 52, one end of which is held to the carriage bed and the other end to the lever 49. In the position shown the lever 49 permits free movement of the dog carrier, but when engaged by the device 42 will be moved to a position to engage the dog carrier or the outer dog. The escapement cannot be operated at this time as the levers 14 cannot be depressed, and thus the carriage is locked against movement, the position of the parts being such that this occurs at the end of a line.

If the device 42 is released by the handle end 46, the carriage may still be moved a certain number of spaces until the end of the lever 49 is engaged by the shoulder or abutment 53 of said device, the distance the carriage is permitted to move being determined by the length of the slot in the device or the distance between the two abutments 51 and 53. The device or element 42 is normally held against pivotal movement by the spring 43, one end of which abuts against a washer 54 held to the rod 55 which supports the spring 43. The lever 49 is first engaged by the end 51 of the device 42, and when the latter is released, as can be done very readily, the outer end of the lever 49 will enter the slot in the device 42 until the shoulder or abutment 53 again engages the same, and moves it on its pivot when the carriage will be positively locked. By this means additional letters may be printed at the end of a line to complete a word if desired.

From the foregoing, it will be evident that simple and efficient means are provided whereby the carriage may be held against movement at the end of the line and then released and again automatically locked in order that one or more characters may be added; that said mechanism is simple in construction and is substantially direct in its action requiring very few parts; and that said mechanism is effective to prevent the key-operated levers from being actuated when the carriage reaches the end of the line.

Having thus described the invention, what is claimed as new is:

1. In a typewriting machine, the combination of a support, a carriage movable along said support, mechanism whereby the carriage may be given a step-by-step movement for letter-spacing, and a line-lock mechanism comprising a pivotally held device movable with the carriage, a horizontally arranged and pivoted lever held to the support under the carriage and having one end adapted to be engaged by said device and its other part adapted directly to engage a part of the feed mechanism to lock the carriage against movement.

2. In a typewriting machine, the combination of a support, a carriage movable along

1. said support, feed mechanism whereby the carriage may be given a step-by-step movement for letter-spacing, and a line-lock mechanism comprising a pivotally held device movable with the carriage, a horizontally movable lever pivotally held to the support under the carriage and having one end adapted to be engaged by said device and its other part adapted directly to engage a part of the feed mechanism to lock the carriage against movement at two distinct points.
2. In a typewriting machine, the combination of a bed, a carriage movable along said bed, feed mechanism whereby the carriage may be given a step-by-step movement for letter-spacing, a device pivotally held to the rear of the bed at one end thereof and having one end slotted, and a lever pivotally held to the carriage bed and having one end thereof adapted to be engaged by the pivoted device and its other end adapted to engage a part of the letter-spacing mechanism to lock the carriage against movement.
3. In a typewriting machine, the combination of a support, a carriage movable along said support, feed mechanism whereby the carriage may be given a step-by-step movement for letter-spacing, a pivotally held device having one end slotted, a lever pivotally held to the support and having a part thereof adapted to be engaged by the pivoted device and having its other end adapted to engage a part of the letter-spacing mechanism to lock the carriage against movement, said line-lock mechanism being shiftable into compact relation to another part of the machine when not in use.
4. In a typewriting machine, the combination of a support, feed mechanism whereby the carriage may be given a step-by-step movement for letter-spacing, and a line-lock mechanism comprising a device movable with the carriage, a lever pivotally held to the support and having a part thereof adapted to be engaged by said device and having its other end adapted to engage a part of the feed mechanism to lock the carriage against movement, said line-lock mechanism being foldable into overhanging relation to the forward part of the machine when not in use.
5. In a typewriting machine, the combination of a support, a carriage movable along said support, feed mechanism whereby the carriage may be given a step-by-step movement for letter-spacing, and a line-lock mechanism comprising a movable device and a lever pivotally held to the support and having a part thereof adapted to be directly engaged by said device and having its other end adapted directly to engage a part of the feed mechanism to lock the carriage against movement at two distinct points.
6. In a typewriting machine, the combination of a support, a carriage movable along said support, feed mechanism whereby the carriage may be given a step-by-step movement for letter-spacing, and a line-lock mechanism comprising a movable device and a lever pivotally held to the support and having a part thereof adapted to be directly engaged by said device and having its other end adapted directly to engage a part of the feed mechanism to lock the carriage against movement at two distinct points.

This specification signed and witnessed this twentieth day of August, A. D. 1913.
